UNITED STATES PATENT OFFICE.

STEPHEN RICHARD AUDIBERT, OF FORT KENT, MAINE, ASSIGNOR OF ONE-HALF TO
DAVID A. COURY, OF FORT KENT, MAINE.

BIT SOCKET.

Application filed December 19, 1927. Serial No. 241,095.

My invention relates to bit sockets, that is, to sockets for interchangeably holding boring or drilling bits.

The object of my invention is to provide an improved bit socket adapted to receive and securely hold bits of all sizes within the capacity of the socket. A further object of my invention is to provide an improved bit socket in which the locking or releasing of the bit is quickly accomplished by a single, substantially instantaneous operation. A further object of my invention is to provide a bit socket in which the bit holding means is locked so as to prevent accidental releasing or loosening of the bit. Other objects will appear hereinafter.

With these objects in view my invention consists generally in a tool shank, a pair of rocker jaws on the shank adapted to grip the bit, a sleeve slidably mounted on the shank to open and close said jaws and a lever for actuating said sleeve. My invention further consists in a device as mentioned further characterized by a second sleeve on the shank and a link connecting the last mentioned sleeve and said lever, whereby swinging of the lever will move the first mentioned sleeve to open or close the jaws. My invention further consists in a bit socket as mentioned in which the second mentioned sleeve is provided with a spring adapted to exert yielding tension on the link and lever when in jaw closing position, and in which the connection between the link and the lever is adapted to pass the line of centers of the lever fulcrum and the point of connection between the link and the second mentioned sleeve, whereby the device is locked in bit securing position. My invention further consists in various details of construction and arrangements of parts, all as will be fully described hereinafter and particularly pointed out in the claims.

My invention will be more readily understood by reference to the accompanying drawings forming a part of this specification and in which—

Fig. 1 is an elevation of a bit socket embodying my invention,

Fig. 2 is a bottom plan view thereof,

Fig. 3 is a section on the line 3—3 of Fig. 2, illustrating the jaws in open position, and

Fig. 4 is a similar view illustrating the jaws in closed position.

Referring now to the drawings 1 indicates a tool shank, which may be either the shank of an auger brace or the shank of a drill press. The upper portion of the shank is preferably cylindrical, as indicated, but the lower portion is squared as indicated at 2. The major part of the squared portion 2 is bifurcated forming recesses 3—3 for a pair of oppositely disposed jaws 4—4. A web 5 extends downwardly a short distance to support a transversely retaining pin 6 upon which the jaws 4 are pivotally mounted. The inner faces of the bifurcated portion are recessed as at 7 to receive the squared head of a bit.

Slidably mounted on the bifurcated end of the shank and enclosing the jaws 4 is a jaw actuating sleeve 8. This has a square bore 9 to fit the bifurcated end of the shank, and the outer faces of the jaws are transversely squared as at 10 to fit in diagonally opposite corners of the bore, as clearly indicated in Fig. 2. These outer faces of the jaws are also concavely curved longitudinally, forming cam edges 11 to be contacted and operated by the upper and lower edges of the sleeve 8. See Figs. 3 and 4. By moving the sleeve upwardly, the lower or bit receiving portion of the jaws are opened, whereas by moving the sleeve downwardly said jaws are closed upon the end or head of the bit. The inner faces of the jaws are preferably formed with squared recesses 12 to receive a squared bit head. The inner faces of the jaws, at their upper ends, are formed with rocker faces 13, whereby the jaws may rock on the lateral faces of the web.

Mounted upon the shank 1, above the sleeve 8, is a second sleeve 14, which is preferably formed with a cylindrical bore 15 terminating in a square bore 16, at its lower end forming shoulders 17. 18 indicates a pin extending transversely through the shank 1, and arranged within the bore 15. Interposed between the pin 18 and the shoulders 17 is a coiled spring 19, which normally tends to force the sleeve 14 downwardly. 20 indicates a stop for limiting the downward movement of the sleeve 14.

Pivottally connected as at 21 to the sleeve 8 is a pair of levers 22 connected at their upper ends by a yoke 23, which, when the lever is in jaw locking position, rests within a recess 24 formed in the face of the sleeve 14. Pivottally connected to the sleeve 14 as at 25 are links 26,

the lower ends of which are pivotally connected as at 27 to the levers 22, preferably adjacent the pivot 21. The arrangement is such that when the levers are thrown into the 5 position shown in full lines in Fig. 1, the pivot 27 will pass beyond the line of centers between the pivots 21 and 25, thereby locking the device against accidental displacement of the lever and loosening of the jaws.

10 It is obvious that with a device of this construction bits of various sizes may be inserted and securely held within the jaws. To open the jaws for the insertion or removal of a fit, the lever is swung downwardly as indicated in 15 dotted lines in Fig. 1. The sleeve 14 will then be in engagement with the stop 20 and through the medium of the links 26 the sleeve 8 will be raised into the position shown in dotted lines in Fig. 1, and in full lines in Fig. 20 3. This forces open the lower ends of the jaws 4. When the bit is inserted the lever is swung upwardly into the position shown in full lines in Fig. 1. This forces the sleeve 8 downwardly until the jaws tightly grasp the 25 bit head or shank. Further movement of the lever will then force the sleeve 14 upwardly against the tension of the spring 19. After the point 27 passes the line of centers of points 21 and 25, the lever 22 will be locked against 30 accidental displacement and thereby prevent accidental loosening of the bit in the socket.

It is obvious that bits of any size may be held, the only difference being that the larger the bit the less movement is required to close the jaws upon the same and greater movement of 35 the sleeve 14 will be required to compensate for the lesser movement of the sleeve 8.

I claim:

1. In a device of the class described a shank, a pair of jaws on the shank, a sleeve slidable 40 on the shank and adapted to open and close said jaws, a second sleeve mounted on said shank, a lever pivotally connected to the first mentioned sleeve, a link pivotally connected at one end to said second mentioned 45 sleeve, the opposite end of said link being pivotally connected to said lever, and a spring associated with the second mentioned sleeve adapted to exert tension on said link when the device is in jaw closing position, 50 substantially as described.

2. A device as set forth in claim 1, in which the pivotal connection between the link and the lever is eccentric to the pivot of the lever, whereby said connection will pass between the 55 line of centers of the connections between the link and the lever and their respective sleeves, when the lever is moved into jaw closing position, substantially as described.

In testimony whereof I have signed my 60 name to this specification.

STEPHEN R. AUDIBERT.
